CLAIM

The ornamental design for the cutting shears, as shown and described.

DESCRIPTION

FIG. 1 is a top left perspective view of the cutting shears; FIG. 2 is a top right perspective view of the cutting shears shown in FIG. 1;

FIG. 3 is a left plan view of the cutting shears shown in FIG. 1;

FIG. 4 is a top right perspective view of the cutting shears shown in FIG. 1 from a higher angle than FIG. 2;

FIG. 5 is a right plan view of the cutting shears shown in FIG. 1;

FIG. 6 is a top plan view of the cutting shears shown in FIG. 1;

FIG. 7 is a bottom plan view of the cutting shears shown in FIG. 1;

FIG. 8 is a front plan view of the cutting shears shown in FIG. 1;

FIG. 9 is a rear plan view of the cutting shears shown in FIG. 1;

FIG. 10 is a lower right perspective view of the cutting shears shown in FIG. 1; and,

FIG. 11 is a lower left perspective view of the cutting shears shown in FIG. 1.

Broken lines illustrating certain elements on the cutting shears are for illustrative purposes only and form no part of the claimed design.
